UNITED STATES PATENT OFFICE

116,991

DESIGN FOR A COMPACT OR THE LIKE

Cecil H. Lawrence, Attleboro, Mass., assignor to Evans Case Company, a corporation of Massachusetts

Application August 30, 1939, Serial No. 86,972

Term of patent 3½ years

To all whom it may concern:

Be it known that I, Cecil H. Lawrence, a citizen of the United States, residing at Attleboro, county of Bristol, and State of Massachusetts, have invented a new, original, and ornamental Design for Compacts or the like, of which the following is a specification, reference being had to the accompanying drawing, forming a part thereof.

In the accompanying drawing Figure 1 is a perspective view of a compact or the like showing my new design.

The dominant feature of my design resides in the surface ornamentation appearing on the side of the compact illustrated.

In the specific embodiment of the design illustrated the side of the compact not shown is substantially plain.

I claim as my invention:

The ornamental design for a compact or the like, as shown and described.

CECIL H. LAWRENCE.
